CLAIM

The ornamental design for an actuator for latch system, as shown and described.

DESCRIPTION

FIG. 1 is a front, top and right side perspective view of our actuator for latch system;

FIG. 2 is a front elevation view thereof;

FIG. 3 is a left side elevation view thereof;

FIG. 4 is a right side elevation view thereof;

FIG. 5 is a plan view thereof; and,

FIG. 6 is a bottom view thereof.

The designations top, bottom, left side and right side are arbitrary in that the actuator for latch system can be used in different orientations.

The portion of the actuator for latch system shown in dotted lines in FIGS. 1-6 is for illustrative purposes only and does not constitute a part of the claimed design.
